US0D1108973S

(12) **United States Design Patent** (10) **Patent No.:** **US D1,108,973 S**
(45) **Date of Patent:** **** Jan. 13, 2026**

(54) **BOTTLE**

(71) Applicant: **Henkel AG & Co. KGaA**, Duesseldorf (DE)

(72) Inventors: **Daniel Peter Sterling**, Fairfield, CT (US); **Luis Ramiro Gutierrez Montenegro**, Stamford, CT (US); **Daniel Taek Kim**, Township of Washington, NJ (US); **Stuart Mark Leslie**, Larchmont, NY (US); **Elizabeth Anne Santarelli**, Westport, CT (US)

(73) Assignee: **Henkel AG & Co. KGaA**, Duesseldorf (DE)

(**) Term: **15 Years**

(21) Appl. No.: **29/950,950**

(22) Filed: **Jul. 5, 2024**

(51) LOC (15) Cl. **09-01**

(52) U.S. Cl.

USPC **D9/543**; D9/575

(58) **Field of Classification Search**

USPC D9/500, 503, 516, 530, 537, 539-540, D9/549-551, 563, 571-573, 574-575, D9/690-691, 694

CPC B65D 1/02; B65D 1/0223; B65D 1/32

(57) **CLAIM**

The ornamental design for a bottle as shown and described.

DESCRIPTION

FIG. 1 is a top isometric view of a bottle showing the claimed design;

FIG. 2 is a bottom isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dashed broken lines in the figures show portions of the bottle that form no part of the claimed design.

The dot-dash broken lines in the figures define the bounds of the claimed design and form no part thereof.

1 Claim, 7 Drawing Sheets
